INVENTOR MAZOLA BRENEMAN
BY HER ATTORNEY Harry Smith

UNITED STATES PATENT OFFICE.

MAZOLA BRENEMAN, OF PHILADELPHIA, PENNSYLVANIA.

DESIGN FOR AN INDICATOR FOR RADIATORS OF AUTOMOBILES.

51,454.

Specification for Design.

Patented Nov. 6, 1917.

Application filed January 22, 1917. Serial No. 143,871. Term of patent 7 years.

To all whom it may concern:

Be it known that I, MAZOLA BRENEMAN, a citizen of the United States, residing in Philadelphia, Pennsylvania, have invented a certain new, original, and ornamental Design for Indicators for Radiators of Automobiles, of which the following is a specification.

In the accompanying drawing—

Figure 1 is a face view of an indicator

for radiators of automobiles showing my new design, and

Fig. 2 is an edge view of the same.

I claim:—

The ornamental design for an indicator for radiators of automobiles as shown.

MAZOLA BRENEMAN.
